DESIGN FOR AN ELECTRICAL RECEPTACLE COVER

Clarence T. Hollingsworth, Highland Park, Mich.,
assignor to Bulldog Electric Products Company,
Detroit, Mich., a corporation of West
Virginia

Application November 23, 1933, Serial No. 49,833

Term of patent 7 years

To all whom it may concern:

Be it known that I, CLARENCE T. HOLLINGSWORTH, a citizen of United States and a resident of Highland Park, in the county of Wayne and State of Michigan have invented the new, original and ornamental Design for an Electrical Receptacle Cover, of which the following is a specification, reference being had therein to the accompanying drawing.

Fig. 1 is a front elevational view of an electrical receptacle cover showing my new design;

Fig. 2 is a side elevation of the cover shown in Fig. 1;

Fig. 3 is a top plan view of the cover shown in Fig. 2;

Fig. 4 is a perspective view to reduced scale of the cover shown in Figs. 1 to 3.

I claim:

The ornamental design for an electrical receptacle cover, substantially as shown.

In testimony whereof, I sign this specification.

CLARENCE T. HOLLINGSWORTH.
